UNITED STATES PATENT OFFICE

157,732

SCREW DRIVER

Robert W. Burgess, Hamden, Conn., assignor to
The Greist Manufacturing Company, New
Haven, Conn., a corporation of Connecticut

Application December 23, 1948, Serial No. 150,329

Term of patent 14 years

(Cl. D93—4)

To all whom it may concern:

Be it known that I, Robert W. Burgess, a citizen of the United States, residing in Bridgeport, in the county of Fairfield and State of Connecticut, have invented a new, original, and ornamental Design for a Screw Driver, of which the following is a specification, reference being had to the accompanying drawing, forming part thereof, in which:

Fig. 1 is a side elevational view of a screw driver showing my new design;

Fig. 2 is a top plan view; and

Fig. 3 is a bottom plan view.

I claim:

The ornamental design for a screw driver, as shown.

ROBERT W. BURGESS.
